UNITED STATES PATENT OFFICE.

WILLIAM H. DANCE, OF CAMBRIDGE, MASSACHUSETTS, ASSIGNOR TO THE DYAR SUPPLY COMPANY, OF CAMBRIDGE, MASSACHUSETTS, A CORPORATION OF MASSACHUSETTS.

DRIER FOR SAND, GRAVEL, &c.

1,230,684.

Specification of Letters Patent. Patented June 19, 1917.

Application filed December 21, 1916. Serial No. 138,171.

To all whom it may concern:

Be it known that I, WILLIAM H. DANCE, a citizen of the United States, residing at Cambridge, in the county of Middlesex and

5 State of Massachusetts, have invented new and useful Improvements in Driers for Sand, Gravel, &c., of which the following is a specification.

This invention has for its object to provide 10 a simple and effective apparatus for drying sand, gravel, and other loose material, by the use of a hydrocarbon flame projected by air pressure into the lower end of a rotating drum which is journaled to rotate on an inclined axis, the higher end of 15 the drum being provided with means for feeding the material into it, and with a stack for inducing an outward flow of vapor and gases from the drum, and the drum being provided internally with means for alternately raising and dropping the material fed into it. The construction and arrangement is such that the green material entering the higher end of the drum is continuously 20 agitated and moved progressively toward the lower end, in an approximately helical path due to the alternate raising and dropping of the material and to the inclination of the drum, the material being progressively subjected to a gradually increasing 25 temperature from the point where it enters to the point where it leaves the drum, and the partially dried material being practically free from contact with the vapor 30 evaporated from the material in the drum, all as hereinafter more fully described.

Of the accompanying drawings forming a part of this specification:

Figure 1 represents a longitudinal section 40 of a drier embodying my invention.

Fig. 2 represents a section on line 2—2 of Fig. 1.

Fig. 3 represents a section on line 3—3 of Fig. 1.

45 Fig. 4 represents a perspective view of the chute alone;

Fig. 5 represents a perspective view showing the chute and the intake portion of the stack operatively related, the drum being omitted.

50 Fig. 6 represents a perspective view of the burner holder at the lower end of the drum and the heat-conducting bed accompanying said holder and arranged over the burner.

Fig. 7 represents a perspective view of a 55 portion of one of the internal wings or buckets attached to the drum.

Fig. 8 represents a section on line 7—7 of Fig. 1.

The same reference characters indicate the 60 same or similar parts in all the views.

The frame of my improved apparatus as here shown includes two longitudinally extending metal I-beams 12, cross-bars 13 connecting said beams, and a frame extension 65 14 projecting from one side of the frame structure formed by the said beams and cross-bars. The said frame is adapted to be supported in an inclined position, as shown by Fig. 1, by suitable supports 16 placed 70 under the beams 12.

The frame is provided with roller bearings, preferably comprising two pairs of grooved rollers 17 journaled in suitable bearings on the frame. 18 represents an 75 open-ended rotary drum of cylindrical form provided with annular peripheral ribs or flanges 19 bearing on the rollers 17, so that when the frame is inclined as shown, the drum is rotatively supported by the rollers 80 17 in an inclined position.

20 represents a fixed inclined chute attached to legs or standards 21, which are suitably attached to the frame, the lower end of the chute being formed to enter the 85 lower portion of the higher end of the drum 18 without contacting with the drum, said lower portion being substantially semicircular, as indicated by Figs. 2, 4, and 5.

23 represents an upright stack, the lower 90 portion of which is widened and cut away at one side to form an intake, the margin of which is formed by a substantially semicircular flange 24 which projects over the upper portion of the higher end of the drum 95 18 without contacting therewith. The stack is supported by suitable means, such as legs or standards 23^a, suitably attached to the frame. The relative arrangement of the chute 20, stack 23, and the higher end of 100 the drum, is such that material inserted in the chute passes by gravity to the interior of the drum, as indicated by the arrow α in Fig. 1, while vapor and gases passing from the higher end of the drum into the intake 105 of the stack are conducted away by the latter, as indicated by dotted arrows in Fig. 1. The chute is provided with a flap valve 25

hinged at 26 and arranged to normally close against the chute, as indicated by full lines in Fig. 1, to prevent steam and gases from escaping through the chute, said valve being adapted to yield to permit the material to pass by it into the drum.

The drum is provided internally with suitable means, such as longitudinally extending wings 28, for alternately raising and dropping the material inserted in the drum, the material being thus distributed and caused to pass through the drum in an approximately helical path when the drum is rotated.

29 represents a burner holder located adjacent to the lower end of the drum, said holder being preferably a frame sufficiently spaced from said lower end to leave the lower portion thereof unobstructed for the discharge of the dried material, as indicated by the arrow *y* in Fig. 1.

The holder 29 supports a hydrocarbon burner which is adapted to be supplied with oil and air under pressure, and may be of any suitable construction. I have shown the burner at 31 in Figs. 1 and 6, said burner being arranged to project its flame into the lower end of the drum 18 and toward the upper end thereof, the flame extending substantially parallel with the axis of the drum.

Accompanying the holder 29 and rigidly secured thereto by suitable means, such as arms 29^a, is a fixed heat-conducting bed 41 which projects into the lower end portion of the drum, is interposed between the burner flame and the top of the drum, and is arranged to be heated by the flame. Such bed is inclined laterally to guide material dropping from the upper portion of the drum across the flame without contact therewith, so that the dropping material does not pass through the flame, and therefore does not take up unconsumed oil. The inclination and arrangement of the bed 41 are such that all the material dropping upon it slides or rolls from the bed and is discharged upon the bottom portion of the drum. The bed becomes highly heated so that it completes the drying of the material discharged upon it. The bed 41 is preferably angular or roof-shaped, as shown by Figs. 3 and 6, so that it presents two inclined faces to the descending material which guide said material in two directions across the flame, without contact therewith. The ridge of the roof-shaped bed is preferably longitudinally inclined so that it is substantially parallel with the upper portion of the burner flame, said flame diverging as it leaves the burner.

60 The portions of the wings 28 which drop material to the bed 41 are preferably provided with extensions 28^a, Figs. 3 and 7, said wings and extensions forming angular buckets adapted to raise the material in masses 28^b, into the upper portion of the

drum. Said masses are gradually discharged and distributed upon the heated bed.

Practically all of the material elevated in the portion of the drum into which the bed 41 projects, is therefore dropped upon the bed and uniformly distributed over the same, so that the material absorbs and conducts away sufficient heat from the bed to prevent the bed from being injuriously heated.

75 32 represents an oil reservoir supported in an elevated position by a platform 33, which in turn is supported by the frame extension 14. An oil conduit 34 extends from the reservoir to the burner 31, oil being supplied to the burner by gravity.

35 represents an air pump supported by the frame and connected by an air conduit 36 with the burner 31.

80 A motor 37, shown somewhat conventionally by dotted lines in Fig. 1, is supported by the frame at one side of the drum and has suitable driving connections with the pump 35, causing the latter to force air under pressure to the burner. Driving connections are also provided between the motor and the drum, whereby the drum is rotated, said connections, as here shown, including a gear 38 driven by the motor and an annular gear 39 surrounding and attached to the drum and meshing with the gear 38.

85 When green material is supplied to the chute 20 it enters the higher end of the drum, and is circulated over portions of the heated surface of the drum and is heated partly by said surface and partly by the hot products of combustion. As each unit of the material progresses through the drum it encounters a gradually increasing temperature, the units being therefore rapidly dried 100 during their passage through the drum. The drying of the units is completed by their distribution over the heated bed 41, the units passing repeatedly down the sloping sides of the bed and escaping from the lower end of the drum, as indicated by the arrow *y*. The vapor and gases are withdrawn from the higher end of the drum by the stack, which induces an outward flow 110 from said higher end.

115 The portions of the wings 28 extending from the higher end of the drum to the zone or portion of the drum occupied by the bed 41, are preferably single, flat radial shelves 120 extending radially toward the axis of the drum, and adapted to discharge or drop the raised material before it reaches the highest or vapor conducting portion of the drum, so that the material is not raised high enough to encounter the vapor resulting from evaporation the material being raised in relatively shallow masses and to a minimum height. The vapor rises to the upper portion of the drum and passes to the stack 125 130

above the lower portion of the drum through which the material circulates and travels. When, however, the material reaches the zone occupied by the bed 41, it is raised by the buckets formed by the wings and then extensions 28^a, in deeper masses and much higher than before, and circulates and travels through the upper portion of said zone, where it is subjected to radiated heat from the drum and bed, and to direct contact with the heated bed. In other words, the material is raised by said buckets in relatively deep masses and to a maximum height. Incidentally the movement of the material 15 toward the lower end of the drum is less rapid in the zone occupied by the bed 41, than in the other portions of the drum, because it is not liberated so quickly by the buckets in said zone, as by the portions of 20 the radial wings not provided with the extensions 28^a. The material is therefore repeatedly discharged on the heated bed, so that it emerges thoroughly dried from the lower end of the drum. There is no vapor 25 in the space between the heated bed and the upper portion of the drum to retard the drying action.

The stack has an outlet at 50 for water of condensation accumulating in its upper 30 portion.

I claim:

1. A drier of the character stated, comprising an open-ended drum mounted to rotate on an inclined axis and having internal 35 means for alternately raising and releasing loose material therein, means for feeding loose material into the higher end of the drum, a fixed burner arranged to project a flame into the lower end of the drum and 40 toward the higher end, and a fixed heat-conducting bed projecting into the lower end portion of the drum, interposed between the burner flame and the top of the drum and arranged to be heated by the flame, said 45 bed being inclined laterally to guide dropping material across the flame without contact therewith and discharge said material upon the bottom of the drum.

2. A drier of the character stated, comprising an open-ended drum mounted to rotate on an inclined axis and having internal 50 longitudinally extending wings adapted to alternately raise and release loose material in the drum, means for feeding loose material into the higher end of the drum, a fixed burner arranged to project a flame into the lower end of the drum and toward the higher end, and a fixed heat-conducting bed 55 projecting into the lower end portion of the drum, interposed between the burner flame and the top of the drum and arranged to be heated by the flame, said bed being inclined laterally to guide dropping material across the flame without contact therewith and 60 discharge said material upon the bottom of the drum.

the drum, portions of said wings being adapted to raise relatively shallow masses of material to a minimum height, while other portions of said wings, in the end portion of the drum, which surrounds the bed, are 70 provided with extensions forming buckets adapted to raise deeper masses of material to a maximum height and distribute said masses upon the bed.

3. A drier of the character stated, comprising an open-ended drum mounted to rotate on an inclined axis and having internal 75 means for alternately raising and dropping loose material therein, means for feeding loose material into the higher end of the drum, a burner arranged to project a flame into the lower end of the drum and toward the higher end, and a fixed roof-shaped heat-conducting bed projecting into the lower end portion of the drum, interposed 80 between the burner flame and the top of the drum, and arranged to be heated by the flame, said bed having two inclined faces 85 adapted to guide dropping material in two directions across the flame without contact therewith, and to discharge said material 90 upon the bottom of the drum.

4. A drier of the character stated, comprising an open-ended drum mounted to rotate on an inclined axis, and having internal 95 means for alternately raising and dropping loose material therein, means for feeding loose material into the higher end of the drum, a fixed burner holder located outside the drum and adjacent to its lower end, the 100 lower portion of said lower end being unobstructed and constituting an outlet for the dried material, a burner supported by said holder and arranged to project a flame into the lower end of the drum and toward 105 the higher end above said outlet, and a fixed heat-conducting bed attached to and projecting from said holder into the lower end portion of the drum above the burner and spaced from the internal surface of the 110 drum.

5. A drier of the character stated, comprising an open-ended drum mounted to rotate on an inclined axis and having longitudinal internal buckets adapted to alternately 115 raise and discharge loose material in the drum, means for feeding loose material into the higher end of the drum, a burner arranged to project a flame into the lower end of the drum and toward the higher end 120 thereof, and a fixed heat-conducting bed projecting into the lower end portion of the drum, interposed between the burner flame and the top of the drum and arranged to be heated by the flame, said bed being inclined 125 laterally to guide dropping material across the flame without contact therewith and discharge said material upon the bottom of the drum, the said buckets being formed at the 130 lower end portion of the drum to raise the

material in masses above the axis of the drum and discharge said masses upon the bed.

6. An apparatus of the class described, comprising an inclined drum having internal projections on its walls, a stack arranged to receive the upper end of said drum, means for heating the interior of said drum, a chute extending through the lower portion 10 of said stack and into the drum and having an external entrance portion arranged to receive loose material, and a flap valve mounted on the wall of said stack so as normally to form a continuation of said wall to close 15 said chute, but to be movable by loose material deposited in the entrance portion of the chute to permit passage of such material along the chute, said chute being inclined so as to permit loose material therein to gravitate into the drum.

7. A drier of the character stated, comprising an open-ended drum mounted to rotate on an inclined axis, a fixed burner arranged to project a flame into the lower end 25 of the drum and toward the higher end, a fixed laterally inclined heat-conducting bed occupying the lower end portion or zone of the drum, and interposed between the burner flame and the top of the drum, the upper portion of the drum between said bed and the higher end constituting a vapor-conducting portion, a stack adapted to conduct vapor and products of combustion from the higher end of the drum, means for feeding 30 loose material into the higher end of the drum, and internal means carried by the drum for alternately raising and releasing said material, said means being adapted to circulate the material wholly below the said 35 vapor-conducting portion, and to carry the material into the upper portion of the zone occupied by said bed.

8. A drier of the character stated, comprising an open-ended drum mounted to rotate on an inclined axis, a fixed burner arranged to project a flame into the lower end 45 of the drum and toward the higher end, the projected flame occupying only a limited

portion or zone at the lower end of the drum, a stack adapted to conduct vapor and products of combustion from the higher end of the drum, means for rotating the drum, material raising and releasing means carried by the drum and acting to cause a circulation and a progressive movement of the material, said means being organized to cause a slower progressive movement and a higher circulating movement in said zone than in the higher portion of the drum, and fixed means in said zone for preventing contact 60 of the material with the burner flame.

9. A drier of the character stated, comprising an open-ended drum mounted to rotate on an inclined axis, a fixed burner arranged to project a flame into the lower end 65 of the drum and toward the higher end, the projected flame occupying only a limited portion or zone at the lower end of the drum, a stack adapted to conduct vapor and products of combustion from the higher 70 end of the drum, means for rotating the drum, material raising and releasing means carried by the drum and acting to cause a circulation and a progressive movement of the material, said means being organized 75 to cause a slower progressive movement and a higher circulating movement in said zone than in the higher portion of the drum, and a fixed laterally inclined heat-conducting 80 bed projecting into said zone and interposed between the burner flame and the top of the drum.

10. A drier of the character stated, comprising an inclined drum having internal projections on its walls, a stack arranged to receive the higher end of the drum and provided above the drum with an outlet for water of condensation, means for heating the interior of the drum, and means for admitting loose material to the drum below the 85 stack, said outlet preventing water descending from the stack from moistening said material.

In testimony whereof I have affixed my signature.

WILLIAM H. DANCE.
